UNITED STATES PATENT OFFICE

ANTONY JACK CAGLIOSTRO, OF NEW YORK, N. Y.

SUGAR DISPENSER

Application filed September 29, 1930. Serial No. 485,229.

This invention relates to sugar dispensers and has for an object to provide a dispenser in which the jar is open throughout the bottom to provide a filling orifice of great area so that the contents may be easily and quickly replenished, said orifice being closed by a flanged base which forms a support for the jar and carries integral therewith a measuring cup, the result of this construction being that the base and measuring cup as well as the interior of the jar may be easily reached for cleaning so that the device may be kept in a sanitary condition at all times.

A further object of the invention is to provide the jar of the dispenser with a flattened portion having a central orifice and constituting a reduced neck to slidably receive the delivery tube, there being adjusting nuts on said tube bearing against the flat inner and outer faces of the delivery neck and adjustably securing the tube to the neck so that the intake funnel thereof may be spaced as desired from the bottom of the measuring cup to facilitate any desired measured quantity of the contents being dispensed when the jar is inverted.

A still further object of the invention is to provide a dispenser having a one piece glass jar which is externally fluted and upon which the screw base is threaded, the fluting of the jar preventing slipping of the jar when grasped during unscrewing of the base to replenish the contents of the jar.

With the above and other objects in view the invention consists in certain novel details of construction and combinations of parts hereinafter fully described and claimed, it being understood that various modifications may be resorted to within the scope of the appended claims without departing from the spirit or sacrificing any of the advantages of the invention.

In the accompanying drawing forming part of this specification:

45 Figure 1 is a longitudinal sectional view through my improved dispenser; and

Figure 2 is a cross sectional view taken on the line 2—2 of Fig. 1.

Referring now to the drawing in which like characters of reference designate similar

parts in the various views, the dispenser is shown to comprise a jar 10 which preferably is formed of glass and is preferably formed cylindrical in contour, the entire bottom of the jar being open to provide a filling orifice of great area and also to permit easy insertion of a cleansing tool for keeping the jar in a sanitary condition. The jar is provided with longitudinal fluting 11 on the exterior of the wall thereof and is furthermore provided externally at the bottom with screw threads 12. The jar is flattened opposite the bottom to provide a reduced neck 13 which is provided with an axial orifice 14.

A disk base 15 closes the open bottom of the jar and forms a support for the jar. The base is preferably formed of metal and is provided with a pair of concentrically disposed annular flanges 16 and 17. The outer flange 16 is formed with screw threads to engage the screw threads 12 of the jar and removably secure the base to the jar. The inner flange 17 is of greater length than the outer flange and is of less diameter than the diameter of the jar. Said inner flange constitutes a measuring cup. By virtue of the measuring cup being integral with the base, when the base is removed the measuring cup may be conveniently kept in a sanitary condition.

Disposed axially in the jar is a tube 18. The tube terminates in a funnel 19 at one end, projecting loosely into the cup 17, and the opposite end of the tube is extended through the orifice 14 in the neck 13 of the jar. A pair of adjusting nuts 20 and 21 are threaded onto the last named end of the tube and bear against the flat inner and outer faces 22 and 23 of the jar neck to adjustably secure the tube in the jar. By loosening the adjusting nuts the tube may be advanced or retracted to vary the distance between the mouth of the funnel 19 and the bottom of the measuring cup 17 in order to increase or decrease the quantity of sugar or other material delivered by the measuring cup into the funnel when the jar is turned upside down.

In operation, assume that the adjusting nuts 20 and 21 have been manipulated to 100

position the funnel 19, as shown in dotted lines in Fig. 1. The jar 10 may now be inverted whereupon the contents of the measuring cup 17 in the space between the throat 24 of the funnel and the bottom 25 of the measuring cup will be dispensed through the tube 18. Should a greater quantity of material be desired at each operation, it is simply necessary to manipulate the adjusting nuts 20 and 21 to position the funnel 19 so that the mouth 26 thereof is disposed near the open end of the measuring cup, that is, is spaced considerably from the bottom of the measuring cup. Now when the jar is inverted, the material in the measuring cup to a depth extending from the bottom 25 of the measuring cup to the throat 24 of the funnel will be dispensed through the tube 18.

Having thus described the invention, I claim:

1. A dispenser comprising a jar open at the bottom, a removable disk base for the jar closing the open bottom thereof, an annular measuring cup integral with the base and of less diameter than the jar, said jar having an integral pouring neck opposite the bottom, a pouring tube removably disposed in said neck, nuts threaded on the tube and engaging the inner and outer ends of the pouring neck for adjustably securing said tube to said neck, and a funnel carried by the tube projecting into said measuring cup.

2. A dispenser comprising a jar having an open bottom and a longitudinally fluted side wall, a disk base for the jar screwed onto the exterior of said side wall, said fluted wall permitting of the jar being grasped without slipping during unscrewing of the disk base to replenish the contents of the jar, an annular measuring cup integral with the base and of less diameter than the jar, said jar having an integral short pouring neck opposite the bottom, a pouring tube removably secured in said neck at one end and terminating at the opposite end in a funnel projecting loosely into said measuring cup and adjusting nuts threaded on the stem and bearing against the opposite ends of the pouring neck for effecting longitudinal adjustment of the tube in the jar to adjust the funnel with respect to the measuring cup.

3. A dispenser comprising a jar having an open bottom to provide a filling orifice of large area, said jar having a reduced pouring neck opposite the bottom, a screw base closing the bottom of the jar and forming a support for the jar, a measuring cup integral with the inner face of the base, a pouring tube removably disposed in the jar and extending through said neck, said tube terminating remote from the neck in a funnel projecting into said measuring cup, the mouth of the funnel being spaced both from the wall and from the bottom of the cup, and a pair of nuts threaded on said tube and bearing

against the opposite ends of said pouring neck for adjustably securing the tube to said neck whereby the tube may be moved longitudinally in the jar to vary the space between the funnel and the bottom of the measuring cup.

4. A dispenser comprising a jar open at the bottom to provide a filling orifice of great area, said jar having a thickened portion opposite the bottom provided with a central orifice and forming a reduced pouring neck, a tube removably disposed axially in the jar and having a threaded portion fitting in said opening in the neck, nuts on said threaded portion of the tube bearing against the inner and the outer ends of the neck and adjustably securing said tube to said neck, a screw base closing the open bottom of the jar and forming a support for the jar, a measuring cup on the inner face of said base, and a funnel integral with the tube and extending into said cup, manipulation of said nuts permitting of the tube being adjusted longitudinally of the jar to vary the space between the funnel and the bottom of the measuring cup.

5. A dispenser comprising a jar open at the bottom and having screw threads on the side wall at the bottom thereof, a base forming a closure for the bottom of the jar and forming a support for the jar, said base having concentric annular flanges integral therewith, the outer flange being threaded to engage the threads of the jar and the inner flange being spaced from the wall of the jar and constituting a measuring cup, said jar having a flattened portion opposite the bottom provided with a central orifice and forming a pouring neck, a tube disposed axially in the jar and having a threaded portion fitting in said orifice in the neck, a pair of adjusting nuts on said threaded portion of the tube bearing against the inner and the outer ends of the neck and adjustably securing said tube to said neck, and a funnel integral with the tube and extending into said cup, manipulation of said nuts permitting of the tube being moved longitudinally of the jar to vary the space between the funnel and the bottom of the measuring cup.

In testimony whereof I affix my signature.

ANTONY JACK CAGLIOSTRO. [I. S.]
